UNITED STATES PATENT OFFICE.

JAMES L. MCQUARRIE AND CHARLES L. GOODRUM, OF NEW YORK, N. Y., ASSIGNEES
TO WESTERN ELECTRIC COMPANY, INCORPORATED, OF NEW YORK, N. Y., A COR-
PORATION OF NEW YORK.

TELEPHONE-EXCHANGE SYSTEM.

1,393,559.

Specification of Letters Patent.

Patented Oct. 11, 1921.

Application filed August 7, 1919. Serial No. 315,828.

To all whom it may concern:

Be it known that we, JAMES L. MCQUARRIE and CHARLES L. GOODRUM, citizens of the United States, both residing at New York, in the county of New York and State of New York, have invented certain new and useful Improvements in Telephone-Exchange Systems, of which the following is a full, clear, concise, and exact description.

10 This invention relates to improvements in telephone exchange systems and has particular reference to an arrangement for controlling selector switches therefor.

An object of the invention is to control the 15 operation of any one of a plurality of equivalent switches by means common to all of them.

Another object is to provide a number of 20 operating mechanisms, each of which is common to a greater number of switches and automatically pre-allotted so as to be temporarily available to a switch to be controlled thereby.

The inventive idea involved is capable of 25 receiving a variety of expressions one of which, for the purpose of illustrating the invention, is shown in the accompanying drawing; but it is to be expressly understood that said drawing is employed merely 30 for the purpose of facilitating the description of the invention as a whole and not to define the limits thereof, reference being had to the appended claims for this purpose.

The drawing is a diagrammatic view of 35 the circuit arrangement employed in connection with the invention.

Briefly, the invention consists in providing a plurality of equivalent switches, one of which is indicated at S. Each switch is 40 provided with a number of sets of contacts A' and A'', etc., and the several sets are associated respectively with operating mechanisms B' and B'', etc. Each mechanism is common to all of the switches, the same being multiplied thereto through the six conductors shown extending from the mechanism. The several sets of contacts A', A'', etc., are preferably arranged in a rotary bank and each is provided with a plunger 45 C such as disclosed in the Keith line switch well known in the art. The operation of this apparatus is the same as in the Keith structure mentioned, and a master mechanism D is provided to control the apparatus.

tus whereby all the plungers C will at all 55 times be positioned before an idle operating mechanism B', B'', etc. For example, assuming that all sets of contacts A', A'', etc., of the switch S are in normal position, when a call is initiated and the subscriber's line is 60 extended to said switch, the plunger C will be operated, in a manner to later appear, to close the set of contacts A'. This operation releases the plunger C from the key shaft which it normally engages, and the closure 65 of the set of contacts A' operates the magnet of the master mechanism D to cause said shaft to be rotated until all the plungers are positioned before the next succeeding idle 70 operating mechanism B', B'', etc. In this 70 manner one of the common mechanisms B' and B'' is pre-allotted for controlling the operation of the particular switch taken for use. In the establishment of a connection, each 75 common mechanism is unavailable for operating some other switch only during the time occupied by the seized switch in extending a calling line. When the seized switch has found an idle trunk, the common mechanism which controlled the operation 80 of said switch, is returned to normal and thus rendered available for another operation.

It is now believed that the invention will be fully understood from the following detailed description of the operation.

When a subscriber at substation 1 removes his receiver from its hook, a circuit is closed to operate a line switch or line finder, (not shown) of any well-known construction, to 90 seize a trunk leading to an idle selector switch. Let it be assumed that the switch S is the one seized by the line switch or finder and that the sets of contacts A', A'', etc., are all in normal position. The selection of the 95 trunk leading to switch S applies ground to the conductor 2 in any well-known manner and closes a holding circuit for release magnet 3 extending from grounded battery, winding of said magnet and conductor 2 to ground 100 at the line switch or finder. Magnet 3 operates and remains in this condition until the call is terminated. A circuit is now closed for plunger magnet 4 which extends from grounded battery, winding of said magnet, 105 back contact and left armature of cutoff relay 5, front contact and armature of magnet 3 to ground. Plunger C is operated by the

energization of magnet 4, in the same manner as in the Keith line switch, to transfer the contacts of set A to their alternate positions. A circuit is then closed for magnet 6 of the master mechanism D extending from grounded battery, winding, armature and back contact of said magnet, side switch wiper 7 in position 1 and contact 8 to ground. This circuit being self-interrupting will cause the side switch wiper 7 to step around until a terminal is reached which has no ground connected thereto. The operation of magnet 6 rotates the key shaft carrying the idle plunger C and when a terminal of the side switch wiper 7 is reached which has no ground applied thereto, magnet 6 will cease to operate and all the plungers will be positioned before an idle operating mechanism B''. In this manner the mechanism B'' which is common to all of the sets of contact A'' of the several switches will be pre-allotted to control the operation of any switch which may be seized subsequent to the seizure of switch S. When this occurs, ground is applied at one of the sets of contacts A'' and the master mechanism D is again operated to pre-allot another common mechanism.

The closure of the set of contacts A' also establishes a circuit for line relay 9 of the mechanism B', said circuit being traceable from grounded battery, right winding of relay 9, contact 10, subscriber's substation apparatus 1, contact 11 and left winding of relay 9 to ground. This relay energizes and closes the circuit for slow-to-release relay 12 extending from grounded battery, winding of said relay, front contact of relay 9 to ground. The switch is now in condition to receive a series of impulses transmitted from substation 1 by the impulse sending device 13.

The first deenergization of relay 9 in response to the first impulse transmitted closes a circuit for slow-to-release relay 14 extending from grounded battery, winding of said relay, front contact and armature of relay 12, back contact and armature of relay 9 to ground. Relay 14 energizes and, together with relay 12, remains in this condition during the transmission of the series of impulses. Energization of relay 14 closes a circuit for escape magnet 15 of the mechanism B' extending from grounded battery, winding of said magnet, armature and front contact of relay 14 to ground. Escape magnet 15 energizes but at this time has no effect upon the side switch which it controls. Each time relay 9 deenergizes in response to the impulses transmitted to substation 1, a circuit is closed for primary stepping magnet 16 extending from grounded battery, winding of said magnet, contact 17, side switch wiper 18 in position 1, front contact 68 and armature of relay 12 and back contact

and armature of relay 9 to ground. Magnet 16 operates to step brushes 19, 20 and 21 of switch S in a group selecting movement. At the termination of the series of impulses, line relay 9 remains energized and opens the circuit for slow-to-release relay 14, which, after an interval, releases and causes the deenergization of escape magnet 15. The release of magnet 15 moves side switch wipers 18 and 22 into position 2. As soon as magnet 15 releases, a circuit is again established for the same, which extends from grounded battery, winding of said magnet, armature and back contact of relay 14, contacts 23 and 24, the normally closed secondary off-normal contact 25 and primary off-normal contact 26 to ground, the latter contact being closed upon the first step of the switch. Magnet 15 again energizes in this circuit but the side switch wipers 18 and 22 remain in position 2 until said magnet deenergizes. When side switch wiper 22 moves from position 1 to position 2, a self-interrupting circuit for the secondary stepping magnet 27 is established which extends from grounded battery, winding, armature and back contact of magnet 27, contact 28 and side switch wiper 22 to ground. Magnet 27 operates to step the brushes 19, 20 and 21 over the terminals thereof until an idle trunk is found. At the first trunk hunting movement of the brushes of the switch, the secondary off-normal contact 25 is opened to break the circuit of escape magnet 15, but this magnet does not release as long as test brush 21 passes over terminals of busy trunks which condition is denoted by ground upon test terminal 29. When test brush 21 reaches the terminal of an idle trunk upon which there is no ground, the circuit for escape magnet 15 is broken and said magnet releases to cause the side switch wipers 18 and 22 to move into position 3.

When the side switch wiper 22 moves into position 3, a circuit is established for the cutoff relay 5, extending from grounded battery, winding of relay 5, contact 30 and side switch wiper 22 to ground. Relay 5 energizes and locks up through its front contact and right armature to conductor 2. Relay 5 energizing opens at its left armature and back contact the circuit for magnet 4 which then releases and thereby returns the plunger C to its normal position, whereupon the contacts of set A' are restored. The return to normal of this set of contacts opens the energizing circuit of line relay 9 which then releases and retracts its armature which in turn causes the release of relay 12. This relay being slow-to-release does not deenergize until a circuit is established for release magnet 31 of mechanism B', which circuit extends from grounded battery, winding of magnet 31, side switch wiper 18 in position 130

3, front contact and armature of relay 12 and back contact and armature of relay 9 to ground. Magnet 31 energizes and operates to return the side switch of mechanism B' 5 to normal whereupon said mechanism will again be available for the purpose of controlling the operation of some other selector switch through a set of contacts similar to A'. The return to normal of the set of contacts A' extends the calling line through to the next succeeding switch. After the brushes 19, 20 and 21 have engaged the terminals of an idle trunk, the completion of 10 the establishment of the connection may be controlled through switches similar to that shown in the drawing or through any other means well known in the art.

If the subscriber should abandon the call during the setting of switch S, an energizing 20 circuit will be established for release magnet 31 through side switch wiper 18 in positions 2 or 3 to ground at the back contact and armature of relay 9, and mechanism B' will be returned to normal as previously 25 described. At the termination of a call, the replacing of the receiver upon its switch-hook at substation 1, first releases the line switch or finder in a well-known manner and the release of this switch removes ground 30 from the conductor 2. This opens the locking circuit of cutoff relay 5 which then releases. The holding circuit for release magnet 3 of the switch S is also opened, and said magnet then deenergizes to restore the 35 switch to normal position, whereupon the same will be available for another operation.

What is claimed is:

1. In a telephone exchange system, a calling line, a plurality of selector switches to 40 which said line may be extended, sets of contacts for each switch, means for pre-allotting one set of contacts to its associated switch, and electromagnetic controlling apparatus common to a plurality of sets of contacts including the pre-allotted set for controlling 45 the operation of the switch with which said pre-allotted set is associated.

2. In a telephone exchange system, a calling line, a plurality of selector switches to 50 which said line may be extended, sets of contacts for each switch, and electromagnetic controlling apparatus common to certain sets of contacts associated with different switches for controlling the operation of one 55 of said switches.

3. In a telephone exchange system, a call-

ing line, a plurality of selector switches to which said line may be extended, sets of contacts for each switch, electromagnetic controlling apparatus common to certain sets of contacts associated with different switches for controlling the operation of one of said switches, and means actuated thereupon for pre-allotting other sets of contacts and an 60 associated common means.

4. In a telephone system, a calling line, a plurality of trunks, a plurality of electromagnetic controlling equipments therefor each having a set of contacts for each trunk, a plunger for each trunk, means for maintaining the plungers of idle trunks in operative relation to an idle controlling equipment, means actuated by the initiation of a call for seizing an idle trunk, means for actuating the plunger of the seized trunk to 70 connect the same to the preselected controlling equipment, and means thereupon actuated for moving the remaining plungers opposite the next idle controlling equipment.

5. In a telephone exchange system, a calling line, a plurality of selector switches to which said line may be extended, sets of contacts for each switch, electromagnetic controlling apparatus common to certain sets of contacts associated with different switches 80 for controlling the operation of one of said switches, and means for returning said common means to normal at the termination of the operation of said switch.

6. In a telephone exchange system, a calling line, a plurality of switches, a plurality of means each common to all of said switches for controlling the operation thereof, whereby to extend said calling line, a plurality of sets of contacts associated with each of said 95 common means, means for operating one of said sets when a line is extended to one of said switches to cause the operation of the common means with which said set is associated, means for pre-allotting another common 100 means and its associated sets of contacts for operation when the first mentioned set is actuated, and means for returning said common means to normal at the termination of the operation of said switch, whereby said 105 common means is again rendered available for another operation.

In witness whereof, we hereunto subscribe our names this 4th day of August, A. D., 1919.

JAMES L. McQUARRIE,
CHARLES L. GOODRUM.
